BRUSH HOLDER FOR DYNAMOELECTRIC MACHINES

William C. Edmundson, Anderson, Ind., assignor to General Motors Corporation, Detroit, Mich., a corporation of Delaware

Application May 13, 1944, Serial No. 535,483

3 Claims. (Cl. 171—324)

1

This invention relates to brush rigging holders and more particularly to brush holders for electric units having a rotatable part.

An object of the present invention is to provide a structure which not only holds two standard width brushes firmly in a receptacle but also allows the brushes to be fed gradually and evenly through the receptacle and against the commutator as the ends of the brushes are worn away.

Another object of the invention is to provide a brush holder for a plurality of brushes which is so designed that attention or manual adjustment of the brushes is entirely eliminated until the useful lengths have been utilized and the replacement of the brushes is necessary.

Another object of the invention is to provide a brush holder assembly which is easily attached to or removed as a unit from an electrical unit, but allows a part of the unit to be easily moved so as to facilitate replacement of brushes when necessary while the unit is attached; thus eliminating the necessity of removing the brush holder assembly from the electrical unit.

Further objects and advantages of the present invention will be apparent from the following description reference being had to the accompanying drawing wherein the preferred embodiment of the present invention is clearly shown.

In the drawing:

Fig. 1 is a plan view of a brush holder embodying the present invention.

Fig. 2 is a sectional view taken on the line 2—2 of Fig. 1 and showing a fragment of a housing in dot-and-dash lines.

Fig. 3 is a view looking in the direction of arrow 3 in Fig. 2.

Figs. 4 and 5 are plan and side views, respectively, of a brush frame utilized in the present invention.

Fig. 6 is a plan view of a spacer.

Figs. 7 and 8 are plan and front views of a stop member used in the present invention.

Figs. 9 and 10 are side and plan views respectively of an arm used in the present invention.

Referring to Fig. 2 a fragment of a casing 20 of an electric unit (motor or generator) is shown. A commutator for the unit is designated by the reference character 21. The elements 20 and 21 are indicated by dot-and-dash lines.

The electrical circuits and connections are not shown or described in the present invention in view of the fact they will be readily understood by those skilled in the art. The circuits or connections are not necessarily any different from the invention disclosed herein.

2

As is well known a motor or generator is provided with current-carrying brushes to conduct current. Referring to Figs. 1 and 2 the brush holder assembly embodying the present invention supports and guides a plurality of carbon brushes 22 which are arranged side by side to engage the outer periphery of the commutator which, in this instance, is extra wide. These brushes are slidably guided in a brush holder assembly indicated generally by the numeral 25. The brush holder assembly is fixed to the casing 20 by screws 26.

The brush holder assembly 25 comprises a plurality of members punched from flat sheet metal and then bent by dies to the desired formations. One of the members comprises a U-shaped frame member 27 including side arms 28 and a yoke 29. The arms 28 are deformed or offset from their normal planes, as at 30, to provide opposed channels 31 and 32. The web or a bottom wall of channel 31 is extended and bent outwardly to form an ear or support 33 for a conducting strap, not shown. The ear 33 is provided with a tapped opening to receive a screw for clamping a conducting strap upon the ear. The free end of each arm is also extended and bent outwardly to provide ears 34 by which the frame member is mounted in position to the casing 20. The yoke 29 is cut away at its upper edge to form notches 35 to form a lug 36 intermediate the length of the yoke.

A lever stop 37 may be formed as illustrated in Figs. 7 and 8. This stop comprises wings 38 which are so spaced that they will straddle the arms 28 and the wings are secured to the arms 28, in any suitable manner, for example, spot welding. The upper edge of the yoke of lever stop is cut away to provide stops 39 disposed on opposite sides of an extension or lug 40. When the lever stop 37 is secured in position the stops 39 will be opposite the notches 35 of yoke 29 and lug 40 will be opposite the lug 36. The yoke of the lever stop is spaced a substantial distance from the yoke 29 and extends across from one arm 28 to the other in parallelism with the yoke 29 to form a box-like or an elongated or rectangular receptacle. This receptacle is preferably divided by a spacer 41 provided with tangs 41a on opposite edges thereof which project through aligned openings formed in the lugs 36 and 40. When the wings 38 are secured to arms 28 of the member 27, the spacer 41 is securely held in position with respect to the members 27 and 37. The tangs 41a on both sides of the spacer 41 are staked and spot welded 55 to their respective members.

Rotatably secured between the arms 28 to pivot on studs 50 is a lever 51 which has a pair of spaced fingers 52 extending from one side thereof, said fingers extend over the stops 39 and into the rectangular receptacle. When brushes are on opposite sides of the spacer 41 each arm engages the top surface of a brush 22 which is slidably supported in the rectangular receptacle. The lever 51 is actuated by a pair of springs 60, each spring having one end hooked over an eye in the lever while the other end is hooked over two lugs provided by a spring support 61 attached to the ears 34 by spot welding. Any desired number of springs or tension members may be used and it is preferable that there should be at least one for each brush if more than one brush is used. The springs 60 operate to rotate the lever in a clockwise direction as viewed in Fig. 2. Due to the tendency of the lever 51 to rotate in a clockwise direction, as viewed in Fig. 2, the fingers 52 engage the tops of the brushes to exert a radial pressure on the brushes so as to press them firmly against the wide commutator 21 and the brushes can move to and from the commutator relative to each other. As the brushes wear off the fingers gradually move in a clockwise direction until one or both of the fingers engage their respective stops 39 whereby further movement of the brush by the finger is prevented. In this way proper engagement of all the brushes with the commutator surface can be assured and disengagement of all the brushes from the surface can be avoided. Since the brushes are capable of moving relative to each other it is important that the brushes are prevented from chattering.

Furthermore, it also is important that the brushes are moved toward the commutator so that the wear to the brushes is equalized. This is accomplished by the lever 51 with its spaced fingers 52 which is sturdy enough to apply greater pressure to a longer brush, but flexible enough to apply this pressure differentially. Thus, when one of the two brushes, in a receptacle is longer than the other, the longer brush will receive the greater pressure and consequently take the greater proportion of the load current. When this action occurs the longer brush will wear more rapidly. This wear of the longer brush will continue until its length is such as to equalize the pressure and the load between the two brushes.

One important advantage of the construction is to correct unequal wear of brushes in a heavily loaded generator when an unequal heat distribution is present. The present invention continuously corrects unequalized wear of the brushes by the action of the lever as described and the useful lives of the brushes are prolonged. It has been found that such action of the lever extends the useful life of a brush, not in the ratio of just two to one, but five or ten to one, since the brush, in the usual instance of independent brush fingers, which first assumes the greater portion of the load will heat up enough to continue to carry the greater load. This will result in rapid wear to destruction, since the brushes are loaded to capacity when sharing equally.

It will be seen that, by using a biased pivoted lever having spaced fingers, each finger engaging, respectively, the wear of the brushes will be equalized. This arrangement also makes it possible to change the brushes very easily. In order to remove the brushes 22 from the receptacle the

5 fingers are moved in a counterclockwise direction against the action of springs 60 until the free end of the fingers is passed the inner yoke 37 to permit easy removal of the worn brushes and new brushes to be inserted in the receptacle. Thus, the necessity of detaching any part of the brush holder assembly to replace the brushes is eliminated.

While the embodiment of the present invention as herein disclosed, constitutes a preferred form, it is to be understood that other forms might be adopted, all coming within the scope of the claims which follow.

What is claimed is as follows:

1. A brush holder assembly for a dynamo electric machine having a frame and a commutator comprising in combination; a pair of sheet metal stampings having a yoke and branches attached thereto, one of said stampings having long branches while the other has short branches, said short branches being hooked under the long branches and secured thereto in a manner so that the yokes are spaced apart to form an elongated opening; a plurality of brushes slidably mounted in the opening and capable of moving relative to each other; ears secured to the long branches at their free ends; a cross-piece attached to the long branches; a lever pivotally mounted to the long branches and beyond the yokes, said lever including fingers extending above the yoke nearest the pivotal point of the lever and into the opening; spring means having one end anchored to the cross-piece and having the other end attached to the lever to move the lever in one direction urging the fingers into engagement with respective brushes to move same against the commutator; and means for attaching the ears to the frame to hold the brush holder assembly in a fixed relation relative to the commutator.

2. A brush holder assembly for an electric motor having a frame and a rotating part, comprising in combination; a pair of sheet metal stampings having a yoke and branches attached thereto, one of the stampings having long branches deformed to provide opposed channels, while the other stamping has short branches which are formed to hook under the long branches so that its yoke will close the gap between the channels 50 of the long branches to provide an elongated opening; means for securing two branches together; means attached to the yokes for dividing the opening into a plurality of brush receiving sockets; a brush mounted in each pocket; a cross-piece attached to the long branches beyond the yokes; a lever pivotally mounted to the long branches beyond the yokes; said lever including integral fingers extending above the yoke nearest the pivotal point of the lever and into respective 60 pockets, said lever characterized by the fact that the lever is rigid enough to apply greater pressure to the brush that is longer than another but flexible enough to apply the pressure differentially; spring means having one end anchored to the cross-piece and having the other end attached to the lever to move same in one direction urging the fingers into engagement with their respective brushes to move same into engagement with the rotating part; and means for attaching the longer branches to the frame of the motor.

3. A brush holder assembly for a dynamo electric machine having a frame and a commutator comprising in combination; a pair of sheet metal stampings having a yoke and branches attached thereto, one of said stampings having its branches

straddling the branches of the other stamping and secured in a manner that the yokes are spaced apart to form an elongated opening; a plurality of brushes slidably mounted in the opening and capable of moving relative to each other; ears provided by one of the stampings; means cooperating with the ears for securing the stampings to the frame; a sheet metal lever pivotally mounted on the branches of one stamping, said lever including a plurality of fingers, one for each brush; means provided by one of the

yokes cooperating with the fingers to limit the movement of the lever toward the commutator when one of the brushes has been worn a predetermined amount; and means for biasing the lever in one direction causing the fingers to abut their respective brushes to move same against the commutator and thus hold the brushes in the opening and allowing ready removal of the brushes from the opening when the lever is rotated in the opposite direction a certain amount.

WILLIAM C. EDMUNDSON.
